UNITED STATES PATENT OFFICE.

OSCAR S. BLAKESLEE, OF LANSING, MICHIGAN.

CLOTH-MEASURING MACHINE.

1,024,764.

Specification of Letters Patent. Patented Apr. 30, 1912.

Application filed June 24, 1911. Serial No. 635,185.

To all whom it may concern:

Be it known that I, OSCAR S. BLAKESLEE, a citizen of the United States of America, residing at Lansing, in the county of Ing-
ham and State of Michigan, have invented
certain new and useful Improvements in
Cloth-Measuring Machines, of which the fol-
lowing is a specification, reference being had
therein to the accompanying drawings.

10 In handling cloth more especially for the
retail trade it is desirable that the same be
measured rapidly and accurately and be
folded ready for wrapping when severed
from the bolt. If this be done by hand there
15 is liability to error owing to the stretching
of the cloth.

This invention relates to a cloth measur-
ing machine wherein the cloth is so handled
as not to be stretched or allowed to slacken
20 during the measuring process and whereby
a measured portion is folded neatly for
wrapping after it has been severed from the
bolt.

The invention consists in the matters here-
25 inafter set forth, and more particularly
pointed out in the appended claims.

In the drawings, Figure 1 is a plan view
partially broken away of a machine embody-
30 ing features of the invention; Fig. 2 is
a view in side elevation thereof partially
broken away; Fig. 3 is a view in longitudi-
nal section.

As herein indicated a horizontal table 1
is mounted on a suitable frame 2 near one
35 end of which are a plurality of tumbler rolls
3 arranged in a segment of a circle below
the plane of the table. An endless belt 4
surrounds these rolls, the forward one of
40 which is driven by a belt connection indi-
cated at 5 from a pulley 6. An independent
idler 7 is mounted with its upper periph-
eral portion substantially tangent to the
plane of the table between the table and the
45 rolls 3. A shaft 8 on which the pulley 6 is
mounted is journaled in the frame of the
table and is driven by a gear train indi-
cated at 9 at the opposite side of the table
from the pulley, a crank handle 10 or like
50 means being used to turn the train. A drive
roll 11 is mounted on the shaft 8 to extend
through a slot or opening 12 in the table
and coöperate with a presser roll 13 jour-
naled in suitable bearings above the table,
the bearings being projected by springs 14
or the like so that the presser roll yieldingly
55 contacts with the drive roll. A measuring
wheel 14' is mounted on an arbor that is
rotatable in a bearing arm 15. The latter
extends from a base plate 16 hinged to the
side of the frame 2 so that the wheel 14' nor-
60 mally rests on the table bed although it may
be swung back in a vertical arc if desired.
The journal of the wheel 14' is connected
with any preferred kind of registering train
indicated at 16' having an index wheel with
65 unit marks or divisions showing linear meas-
ure, that is, yards, feet and inches, and cut-
ting mechanism is disposed on the table be-
tween the measuring device and the feed
rolls. This may be of any suitable form
70 but as herein indicated it preferably con-
sists of a flat bar or shoe 17 swiveled at one
end to a stud 18 and arranged to lie either
at right angles or at 45 degrees to the main
axis of the table. A shear plate 19 is se-
75 cured on its shoe 17 with one edge parallel
to a flange 20 on the shoe. A clamping bar
21 held in parallel spaced relation with a
guide bar 22 by an outer bracket 23 and
inner hinge 24, is pivoted by the latter to a
80 bracket or angle plate 25 on the shoe 17
with a clamping latch 26 at the outer end
to hold the clamp firmly against the shear
plate 19. A suitably disposed spring 27
counterbalances the parts. A guide bracket
85 28 in sliding engagement with the bar 22
carries at its lower end a stud 29 on which
a cutter disk 30 is journaled, the latter be-
ing dished with a beveled cutting edge which
enters the groove between the shear plate 19
90 and the flange 20 and is held by the latter in
shearing rolling engagement with the edge
of the shear plate when moved across it, a
handle 31 being provided for its convenient
manipulation. A folder drawer is suspen-
95 ded by a pair of suitably disposed and ar-
ranged side frames 33 below the table, the
frames having studs or rolls 34 which travel
in suitable guides 35 arranged on the table
frame 2. To prevent binding a guide yoke
100 36 connected by a pair of stay rods 37 to
the front of the frames 33 travels on a suit-

able guide rod 38 secured as in brackets 39 below the table top. A cam pin 40 on one end of the roll 11 engages cam bars 41, 42, 43 and 44 so disposed on the side of the 5 frame that the revolution of the stud 40 causes the drawer 37 to reciprocate with a speed equal to the periphery of the roll. As herein indicated the bars are disposed in a parallelogram with the sides at angles of 45 10 degrees to the path of motion of the rods. Two oppositely disposed rods 41 and 43 are stationary so that the cam pin bears against their inner faces as it revolves. When it reaches the end of bar 41, it passes out by 15 the adjacent rod 42, which is yieldingly mounted to permit this and then bears against the outer face of the latter rod until the other end is reached, where the rod enters a gap between this outwardly yielding 20 bar and the adjacent fixed one 43 to ride along the inner face of the latter. At the other end of the latter a second outwardly yielding bar 44 allows the roll to pass so as to bear against the outer face thereof; 25 this alternate engagement reciprocates the drawer at the desired rates. The drawer lies below the end of the table 1 adjacent the roll 11.

In operation a bolt of cloth is laid upon 30 the tumbling belt and the end thereof is drawn across the table and passed under the measuring wheel until gripped between the feeding and pressing rolls. Thereafter by turning the rolls the bolt is revolved in such 35 manner as not to cause undue strain to the cloth passing over the table and feeding between the rolls under the rotation of the latter. When the desired amount has been measured the cutter is applied in an obvious 40 manner to make either a straight or bias cut. The cloth passing the rolls falls into the reciprocating folding drawer which by its swinging motion causes the cloth to loosely fold in successive layers which can 45 be readily picked up and wrapped for a customer.

The main feature of the machine is the disposition of the parts so that the cloth is not subjected to any undue strain but is kept 50 moving under even tension, the turning of the bolt on the tumbling belt preventing any jerking of the cloth and the travel of the folding drawer insuring even folds of suitable width.

55 Obviously changes in the details of construction may be made without departing from the spirit of the invention and I do not care to limit myself to any particular form or arrangement of parts.

60 What I claim as my invention is:

1. A cloth measuring machine comprising a table, means near one end thereof for tumbling a bolt of cloth, a pair of coöperating feed rolls near the other end, means

65 operatively connecting the rolls and tumbling means to travel at equal speeds and a reciprocating cloth folder operated by the feeding rolls.

2. In a cloth measuring machine, a table, tumbler rolls transversely journaled near 70 one end thereof with their axes lying in a curved plane, an endless carrier belt traveling around the rolls, an idler at the end of the table adjacent the rolls, a pair of feeding rolls near the other end of the table, 75 means operatively connecting the rolls and tumbler belt to travel at the same peripheral speed, and a reciprocable folder on the table adjacent the feeding rolls adapted to travel at the same speed as the peripheries of the 80 rolls.

3. In a cloth measuring machine, a table, tumbler rolls transversely journaled near 85 one end thereof with their axes lying in a curved plane, an idler roll journaled transversely across one end thereof in substantially tangential relation to the face of the table, a pair of feeding rolls journaled transversely across the table near the other end thereof with the line of contact in substantially the plane of the table, means for rotating the feeding rolls, and means operatively connecting the feeding rolls and tumbler rolls to travel at equal peripheral speed.

4. In a cloth measuring machine, a table, 90 tumbler rolls transversely journaled near one end thereof with their axes lying in a curved plane, an idler roll journaled transversely across one end thereof in substantially tangential relation to the face of the 100 table, a pair of feeding rolls journaled transversely across the table near one end thereof with the line of contact in substantially the plane of the table, means for rotating the feeding rolls, means operatively connecting the feeding rolls and tumbler rolls to travel at equal peripheral speed, and reciprocating folding means on the table near the feeding rolls adapted to travel at a speed 105 equal to the peripheral speed of the feeding 110 rolls.

5. In a cloth measuring machine having a table with cloth measuring means thereon, means for feeding cloth from a bolt past the measuring means consisting of bolt tumbling means on one side of the measuring means, a pair of coöperating feed rolls on the other side thereof, means operatively connecting the rolls and tumbling means to travel at equal speeds and a reciprocating 115 folding device operated by the rolls to travel with a speed equal to the peripheral speed of the rolls.

6. In a cloth measuring machine having a cloth measuring device, a pair of cloth feeding rolls on one side of the device, a reciprocable folder for receiving cloth from the rolls, means on the folder operatively con-

necting it to the rolls to travel at the same speed as the peripheral speed of the rolls, and cloth tumbling means on the side of the measuring device opposite the feeding rolls, 5 operatively connected to said rolls to supply cloth thereto at a speed equal to the peripheral speed of said rolls.

In testimony whereof I affix my signature in presence of two witnesses.

OSCAR S. BLAKESLEE.
